US00D776525S

(12) **United States Design Patent** (10) **Patent No.:** **US D776,525 S**
Trombetta (45) **Date of Patent:** **** Jan. 17, 2017**

(54) **CAPSULE**(71) Applicant: **2266170 Ontario Inc.**, Mississauga, Ontario (CA)(72) Inventor: **Liberatore A. Trombetta**, Ancaster (CA)(73) Assignee: **2266170 Ontario Inc.** (CA)(***) Term: **15 Years**(21) Appl. No.: **29/560,970**(22) Filed: **Apr. 12, 2016****Related U.S. Application Data**

(62) Division of application No. 29/511,583, filed on Dec. 11, 2014, now Pat. No. Des. 757,537.

(51) **LOC (10) Cl.** ..... **09-03**(52) **U.S. Cl.**USPC ..... **D9/429**(58) **Field of Classification Search**

CLAIM

The ornamental design for a capsule, as shown and described.

DESCRIPTION

FIG. 1 is a front perspective view of a capsule showing my new design;

FIG. 2 is a rear perspective view thereof;

FIG. 3 is a left side view thereof;

FIG. 4 is a front view thereof;

FIG. 5 is a right side view thereof;

FIG. 6 is a rear view thereof;

FIG. 7 is a top view thereof; and,

FIG. 8 is bottom view thereof.

The drawings include surface shading lines which represent contour, not surface ornamentation. The dashed broken lines represent structure or features that form no part of the claimed design.

1 Claim, 3 Drawing Sheets

FIG. 2**FIG. 1**

FIG. 4

FIG. 6

FIG. 3

FIG. 5

FIG. 8

FIG. 7
